No. 883,007.

PATENTED MAR. 24, 1908.

A. R. EVEREST.

ALTERNATING CURRENT REGULATOR.

APPLICATION FILED JULY 13, 1906.

UNITED STATES PATENT OFFICE.

AUGUSTINE R. EVEREST, OF RUGBY, ENGLAND, ASSIGNOR TO GENERAL ELECTRIC COMPANY,
A CORPORATION OF NEW YORK.

ALTERNATING-CURRENT REGULATOR.

No. 883,007.

Specification of Letters Patent. Patented March 24, 1908.

Application filed July 13, 1906. Serial No. 326,022.

To all whom it may concern:

Be it known that I, AUGUSTINE R. EVEREST, a subject of the King of Great Britain and Ireland, residing at Rugby, England, 5 have invented certain new and useful Improvements in Alternating-Current Regulators, of which the following is a specification.

My present invention relates to alternating current regulating devices, such as a so-called 10 constant current transformer in which the regulation is effected by varying the co-efficient of mutual inductance between coöperating windings and comprises certain features of construction and arrangement of the windings and the coöperating core of magnetic 15 material whereby the operation of the regulating device may be improved and its construction simplified and cheapened.

In applying my invention to a constant 20 current transformer I arrange the core material in the neighborhood of the coöperating windings, when they are in proximity to each other, at or near the full load condition so that the ratio of the reluctance in the path 25 of the leakage flux between the windings to the reluctance in the path of the flux inclosing the windings is made appreciably higher than when the windings are separated from each other as in the partial or no load condition.

The various features of novelty which characterize my invention are pointed out with particularity in the claims annexed to and forming a part of this specification. For 35 a better understanding of my invention, however, and of the advantages possessed by it, reference may be had to the accompanying drawings and descriptive matter in which I have illustrated and described one of the 40 forms in which my invention may be embodied.

In the drawing, Figure 1 is a sectional elevation, with parts broken away and in section, of a well known type of constant current transformer embodying my invention; Fig. 2 is a plan view of the same transformer; and Fig. 3 is a partial elevation illustrating a modified core construction.

The constant current transformer proper 50 as shown, comprises a core of laminated magnetic material consisting of three vertical legs 1, 2 and 3 which are connected at their upper and lower ends by horizontal legs or branches 4 and 5 respectively. One of the

coils or windings 6 of the transformer is stationary and is shown resting upon the bottom portion 5 of the core. The other coil 7 is connected by links 8 to a pair of flexible members 9, the upper ends of which are connected to the upper ends of arc shaped members 10 carried at the ends of lever arms 11. The lever arms 11 are rigidly connected to a shaft 12 journaled in brackets 13 supported above the core. A lever arm 14 rigidly connected to the shaft 12 supports at its free end 65 an arc shaped member 15 to the upper end of which is connected a flexible member 16. The lower end of the flexible member 16 supports a counterweight 17. The counterweight 17 is not heavy enough to over-balance 70 the weight of the coil 7 which is moved from the position shown in full lines into the position shown in dotted lines under the action of gravity when gravity is the only force controlling the position of the coil. 75

Usually the primary coil having its terminals connected to a suitable source of alternating current is the stationary coil and the secondary coil having its terminals connected to a consumption circuit is the movable coil 80 of the apparatus.

As shown, the air gap between the leg 2 and each of the outside legs 1 and 3 is of constant length between the upper end of the core and the points marked 18. Between 85 the points 18 and 19 the inner sides of the legs 1 and 3 are cut away at an angle. From the points 19 to the bottom of the core the inner sides of the legs 1 and 3 are parallel to the center leg, but the distance between 90 this portion of the inner side of each outer leg and the central leg is, of course, greater than the distance between the upper portions of the legs.

In operation in the no load condition, the 95 coil 7 is held in the position shown in full lines by the magnetic repulsion between the coils 6 and 7. When the coils are so separated the leakage flux between the coils passing through the air gaps between the outside 100 legs and the central leg of the core, is not materially different from what it would be if the lower, inner sides of the outer legs were in the same plane as the upper portions of their inner-sides. When in the partial or full load 105 condition, however, the coil 7 approaches or moves into the position shown in dotted lines, the increased length of the air gap in

the neighborhood of the coils is such that the leakage between the coils is greatly reduced over what it would be if the lower inner sides of the outer legs were in the same planes with the corresponding parts of the upper portion. This reduces the full load reactance of the transformer and permits of a decrease in the length of movement of the movable coil. It also allows the dimensions of the coils to be increased in a direction parallel to the length of the core leg which they surround and reduced in the transverse direction, thus reducing the size and weight of the coils. It also permits of a better cooling of the coils since the radiating surface of the coils is increased in proportion to their volume, and their shape permits of a more efficient cooling by the ascending cooling fluid in contact with it, whether it be air or a liquid such as oil.

The decrease in width of the legs 1 and 3 adjacent the primary coil is of little importance in this type of apparatus though if desired this may be avoided by making the laminæ as shown in Fig. 3.

In the particular transformer construction illustrated, the transformer is inclosed in a metallic casing 20 upon the base of which it is held by suitable clamping bolts 21 which connect the base and a clamping member 22 engaging the upper end of the core. The brackets 13 are shown as bolted to the member 22. The lever arm 14 is shown as passing through a slot 23 in the casing.

While the form of my invention hereinbefore illustrated and described in detail has been found to give excellent results in practice, it will be understood that changes may be made in the form of my invention without departing from its spirit, and that my invention is not limited to use in the relation in which it is shown, and I do not wish the claims hereinafter made to be limited to the particular embodiment disclosed more than is made necessary by the state of the art.

What I claim as new and desire to secure by Letters Patent of the United States, is,—

1. The combination of inductively related windings, means for causing the windings to separate upon increase in current therein and to approach each other upon decrease of current, and means for varying the mean length of the air gap in the leakage path between

the coils as the coils change their relative position to each other.

55

2. In combination, a stationary coil, a movable coöperating coil, a core leg surrounded by the two coils, and a coöperating core leg beside the first, said core legs being so arranged that the distance between them adjacent the stationary coil is greater than at a portion remote therefrom.

3. In combination, a stationary core, a stationary winding, and a movable coöperating winding, said windings and core being so arranged that the mean length of the air gap in the leakage path between the windings is increased as the windings approach each other.

4. In a constant current transformer, the combination of a primary winding, a secondary winding, means for allowing the said windings to move away from each other upon increase in current and to approach each other upon decrease in current in the secondary winding, and means for varying the mean length of the air gap in the path of the leakage flux between said windings as said windings change their relative position.

5. In a constant current transformer, a core leg, a primary winding surrounding said core leg, a secondary winding also surrounding said core leg, and a coöperating core leg, the space between adjacent sides of said core legs being greater in the vicinity of the position occupied by the windings when they are in the full load position than the average length of the gap or space between the portions of adjacent sides of the legs when the windings are separated in the no load or partial load conditions.

6. A constant current transformer, comprising three substantially parallel legs connected by end members, and primary and secondary windings or coils surrounding the middle core leg, one of said windings being stationary and the adjacent sides of the outer core legs in proximity to the stationary winding being undercut.

In witness whereof, I have hereunto set my hand this sixth day of June, 1906.

AUGUSTINE R. EVEREST.

Witnesses:

W. M. F. DAWSON,
ALAN A. POLLOCK.
